CLAIM

The ornamental design for a double hexagonal rotating display rack, as shown and described.

DESCRIPTION

FIG. 1 is a front view of the design;

FIG. 2 is a rear view;

FIG. 3 is a left view;

FIG. 4 is a right view;

FIG. 5 is a top view; and,

FIG. 6 is a bottom view.

The appearance of the vertical panels in the rear of the two hexagonal display units is identical to the appearance of the vertical panels in the front of the two hexagonal display units.
